Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed August 11, 1919. Serial No. 316,544.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to typewriting machines, and is herein disclosed as applied to the so-called Underwood fan-fold billing machine, one form of which is disclosed in the patent to Wernery & Smith, No. 1,132,055, dated March 16, 1915.

The Underwood fan-fold billing machines are usually made of substantial width in order to accommodate comparatively wide forms, but it is sometimes desired to use such machines either continuously, or for more or less long periods of time, upon work requiring narrow webs. According to the present invention, a machine adapted to use a comparatively wide web may be readily transformed into a machine adapted to use two webs which may be kept in the machine side by side, and which may be typed upon alternately, or one of which may be used for considerable periods of time while the other is left idle.

The present invention has especial utility for typing alternately upon complementary work-sheets arranged in continuous or web form, and these webs, which pass through the machine side by side, that is, edge to edge, may or may not be fan-folded webs. By "complementary work-sheets" it is meant that the successive sheets making up one of the webs bear a complementary relation to the successive sheets making up the other web. That is to say, the work-sheets in one web bear a certain definite relation to the work-sheets in the other web, this relation being dependent upon the nature of the forms which may have been printed upon the work-sheets, or it may depend upon the character of the entries which are to be typed upon complementary work-sheets, or it may depend upon both of these factors. For example, in using a continuous billing type-writing machine to write on the successive sheets of a web, and to write also upon other successive web sheets which are complementary to the first, it is necessary to alternate the writing on one sheet with that on the other. With the ordinary fan-fold or

continuous billing type of machine, it would be necessary to remove one of the webs from the machine together with its carbon-holding carriage, and insert the other web in the machine, at the same time placing in position 60 thereon its carbon-holding carriage, thereby causing waste of time and liability of error.

The present invention provides for guiding and laterally gaging a plurality, such as a pair, of webs, or web-sets, side by side to 65 and around a unitary or single-section platen.

In order to enable the utilization of narrow webs without more extensively modifying the structure of the mechanism, the usual 70 bars to which the carbon sheets are clipped may be replaced by bars comprising slitting members adapted to slit the fan-fold webs at their folds, where they are usually perforated, so that the webs are slit on reaching 75 the carbon clip bars or just before reaching them, thus permitting each clip bar to extend across beyond the folds of one fan-fold web and hold a carbon for one or more other fan-fold webs. Inasmuch as the carbon clip 80 bars in the usual fan-fold machine are interchangeable to a large degree, the usual bars may be readily replaced by the bars modified according to the present invention, without the need of even calling in a repair man. 85

In order to guide the webs, the usual edge gages upon the carbon carriage may be supplemented by additional edge gages, so that each fan-fold web, or other form of web-set, is gaged at each edge thereof. The usual 90 rear bar over which the webs are drawn may, if desired, also include edge gages to gage the various webs. The ordinary leading edge gage which extends above the swinging paper table in the usual fan-fold machines 95 may be replaced by a separate end gage for each fan-fold web, said end gages advantageously being all supported from a single bar, which is adapted to be attached where the usual end gage is attached. 100

Other features and advantages will hereinafter appear.

In the accompanying drawings, Figure 1 is a fragmentary perspective view, largely diagrammatic, of an Underwood fan-fold billing machine, showing the present invention applied thereto. 105

Figure 2 is a plan view of a carbon clip bar, showing the carbons clipped thereto and the severing devices attached thereto. 110

Figure 3 is a view similar to Figure 2, but showing an additional clip bar, and diagrammatically showing how the webs are slit.

5 Figure 4 is a sectional end view of the parts and webs seen in Figure 3.

Figure 5 is a perspective view of a slitting device mounted near the middle of a carbon clip bar.

10 Figure 6 is a spread perspective of the edge gages and their mounting upon the carbon paper carriage.

In the fan-fold billing machine, the platen 10 is journaled in a swing frame 11 mounted to swing upon a cross-bar or shaft 12 extending across the carriage 13 so that thereby the platen is displaceable upwardly to provide for straightening out and easing the webs, whereby the webs may be drawn 20 forward and gaged at their leading edges, as heretofore. In order to rotate the platen, there is provided the usual line-space handle 14, which is adapted to rotate the usual line-space wheel 15, which is fast to 25 a pinion 16 and meshes with a pinion 17 upon the shaft 12, which, in turn, meshes with a pinion 18 fast to the axle of the platen 10, with the result that every time the line-space handle is actuated to turn 30 the wheel 15 it turns the platen 10.

The carriage 13 is mounted upon rails including the rail 19, and is fed along in the usual manner whenever any type-bar 20 rises to print upon a work-sheet passed 35 around the platen. The fan-fold billing machine also usually includes a rear extension 21 of the carriage having rails 22 and 23, upon which a carbon carriage 24 is adapted to be reciprocated by a handle 25. 40 The extension 21 also includes a cross-bar 26 connecting the rails 22 and 23, which support the cross-bar 27 over which the initially fan-folded complementary webs 28 and 29 are adapted to be drawn past the carbon carriage and under the platen and up over the front paper table 30. For supporting the rear end of the extension 21, there may be provided a rail 31 fast upon an extension 32 extending rearwardly from 45 the typewriter carriage. The carbon carriage 24 includes the usual foundations 33 at each side, provided with the usual openings 34 into which pins 35 upon carbon-paper clip-bars 36 are adapted to fit 50 inter-changeably.

According to the present invention, each carbon clip-bar 36 may be adapted to slit one fold of each web. Since there are shown two webs 28 and 29, each bar is 55 shown as provided with two slitting members 37 and 38, one being advantageously at the free end of the clip bar, and the other being at such a position as will be convenient to guide the edge of the other web.

65 In addition to the slitting devices 37 and

38, each carbon clip bar is provided with a clip 39 adapted to hold a carbon sheet for each sheet of web upon which a carbon copy is desired, and for the purposes of the present disclosure each clip bar comprises two of the clips 39, one pivoted on the usual pin 40, and the other on a rivet 40^a, so that they may be swung rearwardly away from their clip bar to permit the carbon sheets 41 to be folded over the end of 75 the clip bar and then held to the bar by swinging the clip 39 against them. The flat rivet 40^a permits the adjacent web to slip smoothly over it. Thus it will be clearly seen, as diagrammatically shown in Figure 80 4, that two fan-fold webs having the same number of folds may be slit by the carbon clip bars which extend across them. The slitting devices have been found to be very effective if made in the form shown in Figure 5, in which each slitting device is a wire slotted to slide over the clip bar 36 and to be held thereto as by soldering, the wire also having a turned-over end 42 to prevent its end, by any accident, from mar- 90 ring the surface of the web sheet. An angle of approximately 60° has been found to be a very efficient angle for the slitting device.

For guiding the complementary webs 28 and 29 up to the carbon carriage, each foundation 33 is provided with the usual opening 43, into which a thumb-screw 44 is adapted to be screwed, thus holding in place not only the usual edge gage 45, but also a supplemental edge gage 46 for the free edge of the web, there being on the two foundations taken together enough edge gages to have a separate edge gage for each edge of each web. The edge gages 46 may 105 comprise right-angle extensions 47, which are curved down and then horizontally toward the center to form a straight section 48 reaching almost as far as the edge of the web. At the end of the section 48, the metal is carried rearward at 49 in order to clear the rearmost clip bar 36, and then bent upwardly to form an edge gage 50 against which the edge of the web is adapted to bear. When a form or other suitable stretch 110 of web has been typed, the usual handle 51 is pushed rearwardly to release the swing frame 11, and then the swing frame is swung forward in the usual manner, and the web which has been typed is drawn forward and 115 gaged against the appropriate one of the adjustable end gages 52, of which there is one on each of the extensions or supports 53, extending above the paper table 30. If the table 30 is provided with a roll 54, as 125 it sometimes is, at the top, the roll is cut away at 55 to permit the support 53 to lie nearly at the surface of the table. The two supports 53 may spring from a single bar 56, which is adapted to be held by the usual thumb- 130

screw 57 upon the rear of the paper table. After the web has been gaged, the carbon carriage is pushed rearwardly by the handle 25 until it strikes the usual stop 58.

5 The operation of handling either web is, in general, the same as in the ordinary fan-fold billing machine. In the machine of the present invention, the typing ordinarily is done alternately upon the complementary 10 work-sheets making up the two webs. Should one of the webs not be used, the one not typed for the time being may be allowed to take care of itself, or its end may hang idly over the bar 27. To further guide the webs 15 at the bar 27, the bar, which is usually removable, is provided with the usual screw 59 to enable a suitable number of stops or side gages 60 to be adjusted thereon, so that there is a side gage at the bar 27 for each 20 side of each of the webs.

Variations may be resorted to within the scope of the invention, and portions of the improvements may be used without others.

Having thus described my invention, I 25 claim:

1. In a typewriting machine of the continuous billing or fan-fold type, in combination, a unitary or single-section rotative platen, carbon-holding bars for supporting 30 carbon-sheets between the plies of fan-folded webs arranged side by side and thus fed to the platen, a carbon carriage movable toward and away from the platen at the introductory side thereof and provided at one 35 side of the machine with a support for certain of said bars and provided at the other side of the machine with a support for others of said bars, said bars being of sufficient length to pass in relatively overlapping 40 relation from one to another of said webs and between the plies thereof, and web-severing means at the rear of said bars for slitting said webs at their folds to provide for the passing of said bars from one to 45 another of the initially fan-folded webs.

2. In a typewriting machine of the continuous billing or fan-fold type, in combination, a traveling carriage, a unitary or single-section platen rotatively mounted on 50 the carriage, carbon-holding bars movable upon the carriage to and from the platen at the introductory side thereof, said bars being of sufficient length and so arranged in overlapping relation as to extend from one to 55 another and between the superposed plies of a plurality of webs fed side by side to the platen, and web-slitting devices located at the rear of said bars and movable therewith to sever the plies of said webs one from the 60 other at fan-folds formed therein.

3. In a typewriting machine, the combination with a traveling carriage and a carbon carriage shiftable thereon, of a rear guide over which a plurality of fan-folded 65 webs are adapted to be drawn side by side,

bars upon said carbon carriage upon which carbon sheets for said webs are adapted to be clipped, a pair of gages for each web, adapted to be separately mounted on said carbon carriage, and means for slitting said webs at their folds behind the carbon sheets to enable the bars to carry the carbons rearwardly between the webs.

4. A carbon-paper-carrying blade having a web-severing device attached thereto intermediate its ends, and a separate carbon-paper-clip adapted to hold a separate carbon sheet upon each side of said severing device.

5. In a typewriting machine of the continuous billing or fan-fold type, in combination, a unitary or single-section rotative platen, a carbon carriage movable relatively toward and away from the platen at the introductory side thereof and including a foundation at each side for detachably receiving carbon-holding bars, and a pair of relatively adjustable side-edge gages mounted upon each of said foundations to be relatively adjusted to the width of the respective webs.

6. In a typewriting machine of the continuous billing or fan-fold type, in combination, a letter-spacing carriage, a unitary or single-section platen rotatively mounted 95 on the carriage, a frame forming an extension at the back of the carriage, a carbon carriage movable on said frame extension toward and away from the platen, a plurality of carbon-holding bars mounted upon the 100 carbon carriage and of sufficient length to pass between and separate the superposed plies of a plurality of sets of webs fed side by side to the platen, means for guiding said webs to and past the carbon carriage and 105 said carbon-holding bars thereon, and web-severing means at the rear of said carbon-holding bars to provide for utilizing fan-folded webs.

7. In a typewriting machine, the combination with a carbon-paper-carriage, of a carbon-paper-carrying blade extending inwardly from each side of said carriage, means upon each blade for severing a plurality of folds, means upon each blade for holding carbon sheets thereupon, and guides behind the blades for guiding the web past them.

8. In a typewriting machine, the combination with a carbon-paper-carriage, of a 110 foundation at each side thereof, a plurality of carbon-paper-carrying blades detachably mounted upon said foundations, a plurality of carbon-holding devices arranged along the length of each of said blades, and a web-severing device on each of said blades intermediate its ends and between said carbon-holding devices.

9. In a typewriting machine, the combination with a carbon-paper-carriage, of a 130

- foundation at each side thereof, a plurality of carbon-paper-carrying blades detachably mounted upon said foundations, a plurality of carbon-holding devices arranged along the length of each of said blades, a web-severing device on each of said blades intermediate its ends and between said carbon-holding devices, and another web-severing device carried by a free end of each of said blades.
10. In a typewriting machine, the combination with a carbon-paper-carriage, of a foundation at each side thereof, a plurality of carbon-paper-carrying blades detachably mounted upon said foundations, a plurality of carbon-holding devices arranged along the length of each of said blades, a web-severing device on each of said blades intermediate its ends and between said carbon-holding devices, means for guiding the webs at the carbon-paper-carriage, and separate means for guiding them behind the carriage.
11. In a typewriting machine, the combination with a carbon-paper-carriage, of a foundation at each side thereof, a plurality of carbon-paper-carrying blades detachably mounted upon said foundations, a plurality of carbon-holding devices arranged along the length of each of said blades, a web-severing device on each of said blades intermediate its ends and between said carbon-holding devices, another web-severing device carried by a free end of each of said blades, means for guiding the webs at the carbon-paper-carriage, and separate means for guiding them behind the carriage.
12. In a typewriting machine of the continuous billing or fan-fold type, in combination, a letter-spacing carriage, a unitary or single-section platen rotatively mounted on the carriage, and means for supporting and guiding a plurality of webs side by side to and around the platen from the rear or introductory side thereof, said supporting and guiding means comprising a frame forming an extension at the back of the carriage, and side-edge gages carried by said frame extension for independently guiding both edges of each of said webs.
13. In a typewriting machine of the continuous billing or fan-fold type, in combination, a letter-spacing carriage, a unitary or single-section platen rotatively mounted on the carriage, and means for supporting and guiding a plurality of webs side by side to and around the platen from the rear or introductory side thereof, said supporting and guiding means comprising a frame forming an extension at the back of the carriage, and side-edge gages carried by said frame extension for independently guiding both edges of each of said webs, said gages being adjustable to accommodate webs of different widths.
14. In a typewriting machine of the continuous billing or fan-fold type, in combination, a letter-spacing carriage, a unitary or single-section platen rotatively mounted on the carriage, and means for supporting and guiding a plurality of webs side by side to and around the platen from the rear or introductory side thereof, said supporting and guiding means comprising a frame forming an extension at the back of the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, and a plurality of sets of side-edge gages mounted on the carbon-carriage for guiding both edges of each set of webs.
15. In a typewriting machine of the continuous billing or fan-fold type, in combination, a letter-spacing carriage, a unitary or single-section platen rotatively mounted on the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, and a plurality of sets of side-edge gages mounted on the carbon-carriage for guiding both edges of each set of webs.
16. In a typewriting machine of the continuous billing or fan-fold type, in combination, a letter-spacing carriage, a unitary or single-section platen rotatively mounted on the carriage, a frame forming an extension at the back of the carriage, a carbon-carriage movable on said frame extension toward and away from the platen, a carbon-holding bar mounted at one of its ends on the carbon-carriage and projecting substantially parallel with the platen to a sufficient extent to pass between and separate the superposed plies of a plurality of sets of webs fed side by side to the platen, a plurality of sets of side-edge gages mounted on the carbon-carriage for guiding both edges of each set of webs, and another plurality of sets of side-edge gages mounted on said frame extension at the rear of the carbon-carriage for preliminarily guiding both edges of each set of webs.
17. A carbon-holding device for use in a typewriting machine with a fan-fold web and a set of superposed plies at one side of said web, comprising a carbon-holding bar supported at one end and extending from the supported end, first between adjacent plies of the web to support a carbon-sheet therebetween, and then between adjacent plies of the set to support a carbon-sheet therebetween, and a web-severing device mounted upon said carbon-holding bar in position to sever the adjacent plies at one edge of the fan-fold web to permit one of

the several plies to pass above and the other below the bar.

18. In a typewriting machine of the continuous billing or fan-fold type, in combination, a letter-spacing carriage, a unitary or single-section platen rotatively mounted on the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, a plurality of sets of side-edge gages mounted on the carbon-carriage for guiding both edges of each set of webs, and a web-severing device carried by the carbon-holding bar at a median point thereon to provide for utilizing a fan-folded web adjacent to the mounting end of the carbon-holding bar and whereby said bar may project beyond the severed fan-folded web to and between the superposed plies of a next adjacent web or set of webs, and a separate carbon-holding device mounted upon the carbon-holding bar at each side of said severing device.

19. In a typewriting machine of the continuous billing or fan-fold type, in combination, a letter-spacing carriage, a unitary or single-section platen rotatively mounted on the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, and a separate carbon-holding device mounted upon the carbon-holding bar at each side of said severing device.

20. In a typewriting machine of the continuous billing or fan-fold type, in combination, a letter-spacing carriage, a unitary or single-section platen rotatively mounted on the carriage, a frame forming an extension of the carriage at the rear or introductory side of the platen, a carbon-carriage mounted to travel on said frame extension toward and away from the platen, a plurality of carbon-holding bars substantially parallel with the platen and mounted on the carbon-carriage at opposite sides thereof to project inward in overlapping relation so as to pass between and separate the superposed plies of a plurality of sets of webs fed side by side to the platen, a pair of side-edge gages for each web-set mounted on said frame extension at the rear of the carbon-carriage and laterally adjustable relatively to each other to accommodate web-sets of different widths, a second pair of similarly adjustable side-edge gages for each web-set mounted on the carbon-carriage, a web-severing device carried by the free end of each said carbon-holding bar, and another web-severing device mounted upon each carbon-holding bar intermediate of its ends, whereby a pair of initially fan-folded webs may be used.

21. In a typewriting machine of the continuous billing or fan-fold type, in combination, a letter-spacing carriage, a unitary or single-section platen rotatively mounted on the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, a plurality of sets of side-edge gages mounted on the carbon-carriage for guiding both edges of each set of webs, a web-severing device carried by the carbon-holding bar at a median point thereon to provide for utilizing a fan-folded web adjacent to the mounting end of the carbon-holding bar and whereby said bar may project beyond the severed fan-folded web to and between the superposed plies of a next adjacent web or set of webs, and a separate carbon-holding device mounted upon the carbon-holding bar at each side of said severing device.

22. In a typewriting machine of the continuous billing or fan-fold type, in combination, a letter-spacing carriage, a unitary or single-section platen rotatively mounted on the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, and a separate carbon-holding device mounted upon the carbon-holding bar at each side of said severing device.

23. In a typewriting machine of the continuous billing or fan-fold type, in combination, a letter-spacing carriage, a unitary or single-section platen rotatively mounted on the carriage, a carbon-carriage movable relatively toward and away from the platen at the introductory side thereof, a carbon-holding bar mounted at one of its ends on the carbon-carriage and of sufficient length to pass between and separate the superposed plies of a plurality of sets of webs fed side by side to the platen, and a separate carbon-holding device mounted upon the carbon-holding bar at each side of said severing device.

24. A carbon-holding device for use in a typewriting machine with a fan-folded web and a set of superposed plies at one side of said web, comprising a carbon-holding bar to pass between and to hold separate carbon-sheets between adjacent plies of both the web and the set, and a web-severing device mounted upon said carbon-holding bar intermediate of its ends, to sever the adjacent plies of the fan-folded web at the edge of the web toward the set of plies, to permit one of the severed plies to pass above and the other below the bar.

25. A carbon-holding device for use in a typewriting machine with two fan-folded webs arranged side by side, comprising a carbon-holding bar having a free end and supported at its other end so as to pass between and to hold separate carbon-sheets between adjacent plies of both the webs, a web-severing device carried by the free end of said carbon-holding bar to sever the adjacent plies of one web to enable them to pass on opposite sides of the bar, and another web-severing device mounted upon said carbon-holding bar intermediate of its ends, to sever the adjacent plies of the other web to enable them to pass on opposite sides of the bar.

26. A carbon-holding device for use in a typewriting machine with a plurality of sets of superposed plies, the sets being arranged side by side, comprising a carbon-holding bar to pass between adjacent plies of all of said sets, and a plurality of separate carbon-holding devices, one for each set of plies, on said carbon-holding bar at different locations along its length for holding a corresponding plurality of carbon-sheets

between the adjacent plies of the different sets.

25. A carbon-holding device for a type-writing machine, comprising a carbon-holding bar, a web-severing device mounted upon said carbon-holding bar intermediate of its ends, and a carbon-holding device on the carbon-holding bar at each side of said severing device for holding a separate carbon-sheet on the bar at each side of said severing device.

26. A carbon-holding device for a type-writing machine, comprising a carbon-holding bar having a free end and adapted to be supported at its other end, a web-severing device carried by the free end of said carbon-holding bar, another web-severing device mounted upon the carbon-holding bar intermediate of its ends, and a carbon-holding device on said carbon-holding bar at each side of said intermediate severing device.

27. A carbon-holding device for a type-writing machine, comprising a carbon-holding bar having a free end and adapted to be supported at its other end, a web-severing device carried by the free end of said carbon-holding bar, another web-severing device mounted upon the carbon-holding bar intermediate of its ends, and means for holding a separate carbon-sheet on said carbon-holding bar at each side of said intermediate severing device.

28. In a typewriting machine of the continuous billing or fan-fold type, in combination, a letter-spacing carriage, a unitary or single-section rotative platen, a frame in which the platen is mounted on said carriage to enable it to be displaced therein to provide for the straightening out and drawing forward of a plurality of webs passing side by side around the platen, an independently adjustable leading-edge gage for each of said webs at the delivery side of the platen, and means for supporting and guiding a plurality of said webs side by side to and around the platen from the rear or introductory side thereof, said supporting and guiding means comprising a frame forming an extension at the back of the carriage, and side-edge gages carried by said frame extension for independently guiding both edges of each of said webs, said gages being adjustable to accommodate webs of different widths.

29. In a typewriting machine of the continuous billing or fan-fold type, in combination, a letter-spacing carriage, a unitary or single-section rotative platen, a frame in which the platen is mounted on said carriage to enable it to be displaced therein to provide for the straightening out and drawing forward of a plurality of sets of webs passing side by side around the platen, an independently adjustable leading-edge gage

for each of said sets of webs at the delivery side of the platen, a carbon-carriage movable relatively toward and away from the platen at the introductory side thereof, a carbon-holding bar mounted at one of its ends on the carbon-carriage and of sufficient length to pass between and separate the superposed plies of said plurality of sets of webs as they are fed side by side to the platen, and a plurality of sets of side-edge gages mounted on the carbon-carriage for guiding both edges of each set of said webs, said gages being adjustable to accommodate webs of different widths.

30. In a typewriting machine of the continuous billing or fan-fold type, in combination, a letter-spacing carriage, a unitary or single-section rotative platen, a frame in which the platen is mounted on said carriage to enable it to be displaced therein to provide for the straightening out and drawing forward of a plurality of sets of webs passing side by side around the platen, an independently adjustable leading-edge gage for each of said sets of webs at the delivery side of the platen, a carbon-carriage movable relatively toward and away from the platen at the introductory side thereof, a carbon-holding bar mounted at one of its ends on the carbon-carriage and of sufficient length to pass between and separate the superposed plies of said plurality of sets of webs as they are fed side by side to the platen, a plurality of sets of side-edge gages mounted on the carbon-carriage for guiding both edges of each set of said webs, said gages being adjustable to accommodate webs of different widths.

31. In a typewriting machine of the continuous billing or fan-fold type, in combination, a letter-spacing carriage, a unitary or single-section rotative platen, a frame in which the platen is mounted on said carriage to enable it to be displaced therein to provide for the straightening out and drawing forward of a plurality of sets of webs passing side by side around the platen, an independently adjustable leading-edge gage for each of said sets of webs at the delivery side of the platen, a carbon-carriage movable relatively toward and away from the platen at the introductory side thereof, a carbon-holding bar mounted at one of its ends on the carbon-carriage and of sufficient length to pass between and separate the superposed plies of said plurality of sets of webs as they are fed side by side to the platen, a plurality of sets of side-edge gages mounted on the carbon-carriage for guiding both edges of each set of said webs, said gages being adjustable to accommodate webs of different widths.

gages mounted on the carbon-carriage for guiding both edges of each set of said webs, said gages being adjustable to accommodate webs of different widths, a web-severing device carried by the carbon-holding bar intermediate of its ends to provide for utilizing a fan-folded web adjacent to the mounting end of the carbon-holding bar and whereby said bar may project beyond the severed fan-folded web to and between the plies of a next adjacent web or set of webs, and a separate carbon-holding device for each web-set mounted upon the carbon-holding bar at each side of said severing device.

32. In a typewriting machine of the continuous billing or fan-fold type, in combination, a unitary or single-section rotative platen, a carbon-carriage movable relatively toward and away from the platen at the introductory side thereof and including a foundation at each side of the machine, carbon-holding bars extending from said foundations and so arranged and of sufficient length to pass from one to another and between the superposed plies of a pair of sets of webs fed side by side to the platen, and a pair of relatively adjustable side-edge gages mounted upon each of said foundations for the respective sets of webs and being relatively adjustable to accommodate webs of different widths.

33. In a typewriting machine of the continuous billing or fan-fold type, the combination with a unitary or single-section rotative platen relatively movable into and out of position to clamp superposed plies of a plurality of sets of webs for feeding said sets of webs side by side to and around the platen, of a holder for a carbon-sheet, said holder being supported at one end to be inserted between the plies of said plurality of sets of webs said holder being movable longitudinally of the plies to change the position of the carbon-sheet when the platen is at the non-clamping position, and

separate sets of side-edge gages for independently guiding each of said sets of webs in its approach to said carbon-holder and to the platen.

50

34. In a typewriting machine of the continuous billing or fan-fold type, the combination with a unitary or single-section rotative platen, of means for guiding superposed plies of a plurality of sets of webs with interleaved carbon-sheets side by side into the machine and around the platen so that the normal course of the plies of the sets of webs is tortuous, said guiding means including separate sets of side-edge gages for independently guiding each of said sets of webs in its approach to the platen, and means operable at any rotative position of the platen for raising the platen sufficiently to relieve the interleaved carbon-sheets of binding action and afford a clear path for direct advance of the webs in substantially flat condition.

55

35. In a typewriting machine of the continuous billing or fan-fold type, in combination, a unitary or single-section rotative platen, means for guiding a plurality of sets of superposed webs and carbon-sheets side by side into the machine and around the platen, said guiding means including separate sets of side-edge gages for independently guiding each of said sets of webs in its approach to the platen, said guiding means and said platen being arranged so that the sets of webs pursue a normal tortuous course which causes the carbon-sheets to be bound between the webs, shiftable means for altering the course of the webs in a manner to release the carbon-sheets from such inter-binding action, and means for shifting the released carbon-sheets back to new positions along the webs.
